Matthew W. Mitchell(57) **CLAIM**

The ornamental design for a handheld body massaging device, as shown and described.

DESCRIPTION

FIG. 1 is a perspective view of a handheld body massaging device showing my new design;

FIG. 2 is a left-side view thereof;

FIG. 3 is a right-side view thereof;

FIG. 4 is a front view thereof;

FIG. 5 is a rear view thereof;

FIG. 6 is a top plan view thereof; and,

FIG. 7 is a bottom plan view thereof.

The broken lines shown in the figures are for the purposes of illustrating portions of the handheld body massaging device, which form no part of the claimed design.
